UNITED STATES PATENT OFFICE.

ROBERT E. PEARCE, OF ERIE, PENNSYLVANIA.

CLOSURE FOR MILK-JARS AND THE LIKE.

No. 830,450.

Specification of Letters Patent.

Patented Sept. 4, 1906.

Application filed December 7, 1904. Serial No. 235,862.

To all whom it may concern:

1. Be it known that I, ROBERT E. PEARCE, a citizen of the United States, residing at Erie, in the county of Erie and State of Pennsylvania, have invented new and useful Improvements in Closures for Milk-Jars and the Like, of which the following is a specification.

This invention relates to closures for milk-jars and the like; and it consists in certain improvements in the construction thereof, as will be hereinafter fully described, and pointed out in the claims.

The object of the invention is to provide a closure for milk-jars and the like with a means by which it may be readily removed from the jar and to so form this means as to permit of the closure being replaced in the jar after its removal. Cheapening the construction of the closure also forms one of the objects of the invention, as well as other details, which will appear from the specification and claims.

The invention is illustrated in the accompanying drawings, as follows:

25 Figure 1 shows a plan view of the cap or closure; Fig. 2, a central cross-section through the cap or closure and a jar-top.

A marks the body of the closure; A', the flap which is cut from the body of the closure, preferably having the narrow elongated neck a. A retaining portion a' is left, on which the flap may be swung.

The severing of the edges of the flap from the body of the closure may be accomplished 35 by any well-known paper-cutting mechanism. After the severing of the flap I prefer to subject the closure and the flap, and particularly those portions of the closure and flap adjacent to the severed edges, to pressure. This may be done by any suitable 40 press. These closures are ordinarily made of a fibrous material, and by thus subjecting the edges to pressure the edges are forced

into intimate contact, which provides an efficient seal along the edges of the flap. At the same time the flap is left practically free, so that it may be displaced by pressure of the finger, as clearly shown in Fig. 2, for removing the cap.

I am aware that closures have been formed with flaps which have been partially severed from the body of the closure and also that closures have been formed which have had the flaps or parts of them covered with thin layers of paper, so as to be easily broken. My construction is cheaper than most of these, and the flap can also be readily brought back to its normal position, forming an efficient closure when it is desired to replace the cap in the jar or like articles.

What I claim as new is—

1. In a closure for milk-jars and the like, a sheet having its outer periphery shaped to conform to the opening to be closed; and the flap A' formed in the body of the sheet, a portion of the flap being entirely severed from the sheet and the severed edges of the flap and sheet arranged in intimate contact, the contact being that formed by pressure applied subsequent to the severing of the flap.

2. A closure for milk-jars comprising the sheet A having the flap A' formed in the body thereof; said flap being connected with the body of the closure by an elongated neck forming a hinge connection between the flap and the body of the closure, the balance of the flap being in intimate contact with the closure.

In testimony whereof I have hereunto set my hand in the presence of two subscribing witnesses.

ROBERT E. PEARCE.
